UNITED STATES PATENT OFFICE.

JAMES C. BROWN, OF SAN FRANCISCO, CALIFORNIA.

TRANSOM.

SPECIFICATION forming part of Letters Patent No. 363,984, dated May 31, 1887.

Application filed July 2, 1886. Serial No. 206,993. (No model.)

To all whom it may concern:

Be it known that I, JAMES C. BROWN, a citizen of the United States, residing in the city and county of San Francisco, and State of 5 California, have invented a new and useful Transom, of which the following is a specification.

My invention relates to improvements in transoms; and it consists in a certain device for 10 rendering the same burglar-proof at the same time that it increases the facilities for ornamental finish and superior architectural design and ventilation. It will be readily understood by reference to the accompanying drawings 15 and the letters referring thereto.

Figure 1 is a plan view of a transom with a portion broken away to illustrate the pivots. Fig. 2 is a front elevation showing a door with my improvement attached, having the pivots 20 at the inner edge and the levers and attaching-eyes at the upper ends of the slats attached to the journals or pivots. Fig. 3 is a plan view of one of the slats where the pivots are on the corners and on the same side of the slats. Fig. 25 4 is a plan view of a slat in which the pivots are located centrally on the ends and the connecting-eye on one of the edges midway the ends. Fig. 5 is a plan view of a slat which is pivoted centrally and has the lever and connecting-eye attached to the pivot. Fig. 6 is an 30 end view of the slat-frame similar to that shown in Fig. 4. Fig. 7 is an end view of the same as shown in Fig. 3. Fig. 8 is a broken plan view of the same as shown in Figs. 4 and 5. Fig. 9 is a front elevation of a transom with 35 the slats pivoted centrally. Fig. 10 is a transverse section of the frame on the line *x* of Fig. 1.

The following is the construction of my improved transom: I generally form the transom-frame in halves, A B, (shown in Figs. 1 and 10,) of any suitable light casting; but, when required, they may be stamped out of malleable sheet metal, with the journal-bearings for 40 the slats formed so that as the sides or halves of the frame are brought together upon the journals of the slats they are allowed to turn freely in the same.

The object of casting or otherwise forming

the frame A B in halves is to render the same 50 more portable, as well as cheaper and more easily constructed.

C represents a narrow strip of glass. D represents a frame inclosing the two ends and one side. E represents a rod connecting the ends 55 of frame D and completing the inclosure of the glass-slat C, as shown in Fig. 3. It also forms the pivots P for the slat or strip C.

F and G in Fig. 8 represent the two parts 60 of the frame shown in Figs. 4 and 5.

S and S' represent the screw-holes and pivot-bearings in the transom-frame, and S² represents screws which engage the openings S and secure the two halves A B together.

When arranged to form a transom, the slats 65 described form an arrangement similar in appearance to the "Venetian blind." The glass of the slats are formed of glass all of one color or any combination and arrangement of colors, to suit the taste or requirement.

I form the slats all of thin sheet metal when 70 no light is required to be admitted through the transom.

The frame of the transom being firmly attached, and the slats being too close together to 75 admit of egress, it will be seen that it is rendered practically burglar-proof.

The frame A B is screwed fast against the transom-opening, or it may be attached to a 80 separate transom-frame.

Having thus described my invention, what I claim, and desire to secure by Letters Patent, is—

The combination, in a transom, with a fixed metallic frame, A B, made in halves and having a series of openings, S', of a series of metallic slat-frames, each provided with a pane of glass and having pivots to engage the openings S' in the frame A B, a rod connected with said slat-frames, and means, substantially as described, for operating said rod to simultaneously open and close the slat-frames, substantially as set forth.

JAMES C. BROWN.
